UNITED STATES PATENT OFFICE.

MARTIN ADAMSKI, OF CLEVELAND, OHIO.

WHEELED WINDMILL TOY.

1,371,834.

Specification of Letters Patent. Patented Mar. 15, 1921.

Application filed October 6, 1920. Serial No. 414,967.

To all whom it may concern:

Be it known that I, MARTIN ADAMSKI, a citizen of the United States of America, residing at Cleveland, in the county of Cuyahoga and State of Ohio, have invented certain new and useful Improvements in Wheeled Windmill Toys, of which the following is a specification.

This invention relates to certain new and useful improvements in wheeled windmill toys and the primary object of the invention is to provide a toy of this kind which is extremely simple and durable in construction and capable of being cheaply and easily manufactured.

Another object of the invention is to provide a windmill toy including a windmill structure mounted upon a wheeled support, with operative connections between the wheels of the support and the windwheel whereby, when the toy is drawn by a child, said wheels are revolved and the toy will have the appearance of a miniature windmill.

With the above general objects in view and others that will be come apparent as the nature of the invention is better understood, the same consists in the novel form, combination and arrangement of parts herein-after more fully described in connection with the accompanying drawings and in which like reference characters indicate similar parts throughout the several views.

In the drawings,

Figure 1 is a view mainly in side elevation, but partly broken away and in vertical section of a toy constructed in accordance with the present invention.

Fig. 2 is a rear elevational view thereof, Fig. 3 is a horizontal sectional view taken on a plane slightly above the belt guide of the device shown in Fig. 1,

Fig. 4 is a plan view of the blank from which the hood of the windmill structure is formed,

Fig. 5 is a similar view of the blank utilized for both the front and rear walls of the windmill structure,

Fig. 6 is a still further similar view of the blank from which the base of the windmill structure is formed, and

Fig. 7 is a perspective view of the belt guide.

Referring more in detail to the several views, the present invention embodies a wheeled support including a windmill base

which is formed from the blank 5' of Fig. 6. This blank is a substantially rectangular sheet of metal provided with marginal portions 6 which are bent at right angles upon the lines 7 and which are centrally apertured as at 8, the central portion of the blank being provided with a comparatively large rectangular opening 9 for a purpose which will presently become apparent.

An axle 10 is journaled in the marginal portions 6 by passing through the apertures 8, and this shaft is held in the usual manner against longitudinal movement relative to the base 5 by means of the stop members 11 rigidly carried thereby at the inner sides of the marginal portions 6. Supporting wheels 12 are fastened upon the ends of the shaft or axle 10, and these wheels may be of any preferred form although the construction of the same disclosed is desired. As shown, these wheels are each composed of a sheet metal rim or hoop 13 provided with spokes in the end of crossed strips 14 which are flanged at their outer ends as at 15 and riveted through said flanges to the hoop 13 as at 16, the strips 14 being rigidly connected where they cross by soldering or the like and the axle 10 being fastened in the central portions of said strips 14 as 85 clearly shown in Fig. 1 by soldering or the like.

A windmill housing structure is mounted upon the platform 5 and includes a hood 17 formed by bending the blank 17' of Fig. 4 into substantially inverted U-shaped form so that the opposite end edges of said blank rest upon the platform 5 as seen in Fig. 2. The hood 17 thus forms the top and side walls of the housing structure, and front 90 and rear walls of similar formation and indicated at 18 are secured in the ends of the hood as best seen in Fig. 1 to provide an ornamental inclosure. The walls 18 are formed from blanks such as the blank 18' 95 of Fig. 5, and this blank is provided with an upper bendable tongue 19 adapted to pass through the slot 20 of the blank 17' when forming the rear wall and through a similar slot 21 of the blank 17 when forming the front wall, said slots 20 and 21 being provided adjacent the longitudinal edges of the blank 17', at the central portion of the latter. After the tongues 19 of the walls 18 are passed through the slots 20 and 21 they 110 are bent at right angles against the outer face of the hood 17 as shown in Fig. 1. The

walls 18 are further each provided with side bendable tongues 22, and these tongues of the rear wall are directed through slots 23 provided in the blank 17' adjacent the ends of the latter and in alignment with the slot 20, while the tongues 22 of the front wall are directed through similar slots 24 in the end portions of the blank 17' and in alignment with the slot 21. These tongues 22 are also bent at right angles against the outer face of the hood. A pair of tongues 25 are further provided on the lower edge of each wall 18, and the tongues 25 of the rear wall are directed through a slot 26 in the blank 5' while said tongues 25 of the front wall are directed through a similar slot 27 in said blank 5'. The tongues of each pair 25 are bent at right angles in opposite directions into engagement with the under-surface of the platform 5 as best seen in full lines in Fig. 1 and in dotted lines in Fig. 3. The entire housing structure is thus rigidly assembled and secured upon the platform.

A grooved pulley 28 is rigidly fastened upon the central portion of the axle 10 so as to partially project upwardly through the opening 9 of the platform 5 within the hood 17, and the flexible member or belt 29 passes around said pulley 28 as well as upwardly and around another cylindrical pulley 30 which is journaled in the upper end of the housing. The pulley 30 is secured upon a shaft 31 which extends through aligned openings 32 provided in the front and rear walls 18, and the forward end of said shaft 31 is threaded as shown. The windwheel is fastened upon this forward end of the shaft 31 and preferably consists of a pair of double blade members 33 and 34 which cross each other at right angles and which are slidably received upon the screw threaded end of the shaft 31 and rigidly clamped in proper relative position between nuts 35 and 36 respectively threaded upon the shaft 31 after and before the windwheel members are placed thereon. By adjusting the nuts longitudinally of the shaft 31, the position of the windwheel may be changed as indicated by dotted lines in Fig. 1.

As the pulley 28 is arranged with its axis of rotation at right angles to the axis of rotation of pulley 30 the belt 29 is twisted and in order to properly guide said belt, the latter passes through a guide 37 consisting of a single piece of wire coiled at its central portion to provide a belt guiding loop 38 and flattened at its ends as at 39 to provide bendable tongues which pass through apertures 40 of the walls 18 and are bent or clenched against the outer faces of the latter. A comparatively long handle, only part of which is shown at 41 is riveted centrally to the forward edge of the platform 5, the rivets passing through perforations 41'

shown in Fig. 6, and by means of said handle the toy may be drawn or pulled forwardly for causing rotation of the supporting wheels 12. This imparts rotation to shaft or axle 10 and pulley 28 from which the rotary motion is transmitted to shaft 31 and the windwheel through the belt 29 and pulley 30. Forward movement of the toy thus produces the effect of a miniature windmill in operation and the general appearance of the device as a whole is given a realistic atmosphere.

It is believed that the construction and operation as well as the advantages of the present invention will be readily understood and appreciated from the foregoing description.

Minor changes may be made without departing from the spirit and scope of the invention as claimed.

What is claimed as new is:

1. A wheeled windmill toy including a wheeled platform, a sheet metal inverted U-shaped hood having bent tongues passing through said platform and securing the hood on the latter, front and rear wall members having bent tongues passing through said hood and securing said wall members in the opposite ends of the hood to form with the latter a windmill housing, a shaft journaled in the upper end of the housing through said front and rear walls and having a windwheel secured upon the forward end thereof exteriorly of said housing, and means including a pulley upon said shaft operatively connected to the wheels of said wheeled support for causing rotation of said windwheel upon forward movement of the toy.

2. In a windmill toy, a platform formed of a rectangular sheet metal member with its side marginal portions bent downwardly at right angles, an axle journaled through said downwardly bent portions and having supporting wheels rigidly fastened upon the ends thereof, said platform being provided with a central opening, a pulley rigidly fastened upon said axle and projecting upwardly through said central opening, a sheet metal housing including an inverted U-shaped housing having attached front and rear wall members provided with bent tongues passing through the platform and securing the housing on said platform, a shaft journaled in the upper end thereof with its axis of rotation at right angles to the axis of said axle, a windwheel upon the forward end of said shaft, a pulley upon said shaft within said housing, and a twisted belt passing around both aforesaid pulleys whereby rotation of said supporting wheels will cause rotation of said windwheel.

3. In a windmill toy, a platform formed of a rectangular sheet metal member with its side marginal portions bent downwardly at right angles, an axle journaled through

said downwardly bent portions and having supporting wheels rigidly fastened upon the ends thereof, said platform being provided with a central opening, a pulley rigidly fastened upon said axle and projecting upwardly through said central opening, a housing rigidly fastened upon the platform and having a shaft journaled in the upper end thereof with its axis of rotation at right angles to the axis of said axle, a windwheel upon the forward end of said shaft, a pulley upon said shaft within said housing, a twisted belt passing around both aforesaid pulleys whereby rotation of said supporting wheels will cause rotation of said windwheel, and a guide for said belt within the housing including a wire member with a central coiled guide portion and with bent ends passing through the housing to secure the guide to the latter.

4. In a windmill toy, a platform formed of a rectangular sheet metal member with its side marginal portions bent downwardly at right angles, an axle journaled through

said downwardly bent portions and having supporting wheels rigidly fastened upon the ends thereof, said platform being provided with a central opening, a pulley rigidly fastened upon said axle and projecting upwardly through said central opening, a sheet metal housing rigidly fastened upon the platform and having a shaft journaled in the upper end thereof with its axis of rotation at right angles to the axis of said axle, a windwheel upon the forward end of said shaft, a pulley upon said shaft within said housing, a twisted belt passing around both aforesaid pulleys whereby rotation of said supporting wheels will cause rotation of said windwheel, said housing including a transversely disposed substantially U-shaped inverted hood member, and sheet metal front and rear wall members provided with bent tongues securing the same within the ends of said hood and securing the housing upon the platform.

In testimony whereof I affix my signature.
MARTIN ADAMSKI.
